UNITED STATES PATENT OFFICE.

WALTER H. BENTLEY, OF SAN JOSE, CALIFORNIA.

LABELING PROCESS.

Application filed April 23, 1924. Serial No. 708,456.

The present invention relates to processes for labeling and lacquering cans of various kinds, after they have been sealed, such as cans of fruit, vegetables, soups, paints and other materials contained and marketed in sealed cans.

More particularly the invention relates to the lacquering of cans either before or after labels have been applied thereto, and is especially adapted for use in the canning of foods, where attractive external appearance of the cans and labels, sealing of minute holes, and the prevention of rust are highly desirable.

It is well known that labels are printed for application to the cans, are dull in appearance, and that by varnishing or lacquering the labels after printing, the labels become bright, glossy, and attractive. It is accordingly the practice of canners to demand from the printers labels that are varnished or lacquered after the printing. Such varnishing of the labels is an expensive and irksome process for the printer and is carried out by passing the labels as they leave the printing press in wide sheets over rolls which apply the lacquer, and then through a steam heated dry box many feet in length until the varnish is no longer tacky, before they may be piled one on top of the other for shipment. A great amount of spoilage occurs due to piling of the labels before the varnish is sufficiently dry. It is also necessary to use quick drying varnishes which produce a poor finish as compared with slower drying varnishes, because of the great amount of space necessary to dry the labels being turned out at high speed by the presses.

In the canning of foods, such as vegetables, soups and the like, the usual process is that of putting the material in cans, then cooking the material and sealing the cans. After sealing, the cans are allowed to cool from 24 to 36 hours before labeling and packing in boxes. In this process the cans are subjected to a slight rust, and after the labels are applied it is found that after a time, fine pin holes of rust will eat into the can and cause spoilage of the material. A further reason of spoilage of the canned materials has been found to be caused by minute holes initially in the cans which have escaped detection. To overcome this latter defect it has been proposed in United States Patent No. 1,380,610, to dip the cans in

lacquer directly as they come from the sealing machine before they are labeled, and while at a high temperature. This has been found to be impractical because when the cans are dipped by this process a considerable vacuum exists therein, and the liquid lacquer or varnish is forced into the fine holes before it dries and taints the material causing immediate spoilage of the canned material.

I have found it possible to overcome the difficulties in lacquering both the labels and cans in a single, continuous process which produces a higher gloss on the labels than has been heretofore obtainable, coats the cans in a manner to prevent rust, effectually seals minute holes in the cans without drawing the lacquer therethrough and spoiling the contents, and delivers the cans ready for immediate packing and shipment, without the delays usually incident to the cooling storage, between the sealing and labeling of the cans. This is generally effected by the steps of applying unvarnished labels to the cans, varnishing or lacquering the labeled cans, cooling the cans if necessary, for a short time, and then packing them in the boxes for shipment. In the disclosure of the preferred form hereinafter set forth, it will be understood that certain of the steps for example, the step of labeling before lacquering may be omitted or altered without departing from the spirit of the invention which is to be limited in scope only by the appended claims.

The drawing shows schematically an arrangement of apparatus for carrying out the process in continuous manner in connection with the canning of foods.

In the canning apparatus 1 which may be of any usual type, the material is cooked and sealed in cans 2 and the sealed cans may then be partially cooled, if desired. Cans 2 are sealed in the usual manner to have beads or rims formed around the top and bottom edges thereof, and are discharged into a gravity tract or conveyor 3 in which they may pass continuously to any well known form of labeling machine 4. In labeling machine 4 the printed but unvarnished labels are applied to the cans which then are passed into a gravity tract or conveyor 5 from which they are discharged to a tract or conveyor 6 of spray chamber 7. The cans preferably roll through chamber 7 on their top and bottom beads, but may of course be carried

through in suitable conveyors. A plurality of spray nozzles 8 are arranged in chamber 7 in such manner that a fine spray of lacquer is discharged into the chamber and is uniformly deposited on cans as they roll or are passed therethrough. Excess lacquer may be drawn off from bottom of the tank through a pipe 9 by means of a lacquer pump 10 and forced back through 11 into a storage and pressure tank 12 to be again passed through the nozzles 8, or any other suitable spray arrangement may be utilized. The cans are preferably still relatively warm or hot when 15 they reach the spray chamber and the fine spray first deposited thereon immediately hardens a sufficient amount to effectually seal any small holes which may exist in exposed metal portions. As the labeled can proceeds through the chamber it is completely 20 and uniformly covered with a suitable thick film or coating of lacquer. The application of the lacquer to the still warm or hot cans by spraying produces a relatively hardened 25 thin layer of lacquer in contact with the can, and this first layer will seal any minute holes and at the same time will be sufficiently hardened as deposited so that it will not be drawn into the cans, while the remaining 30 layers will be hardened to a less degree, so that as the cans are discharged from the spray chamber, the outer surface of lacquer is still tacky.

From the spray room the completely lacquered and sealed cans are passed over a series of tracks or conveyors 13 through a chamber 14 for a relatively short time, and during which time cooling and drying air currents may be passed over the cans by 35 means of a circulating fan 15 or in any other suitable manner. The cans may be kept in the drying and cooling chamber 14 for an interval as short as a fraction of a minute, and may then be immediately packed while 40 still tacky and warm. No harm is done by packing the cans before the coating is thoroughly dried because the labeled surfaces are prevented from contacting with each other due to the rims or beads on the cans 45 which act as spacers and a slow drying varnish which will produce a high gloss may therefore be used. The cans are also not injured if shipped while warm as the coating effectually prevents rusting of the cans 50 which might otherwise become serious.

It will be apparent that a marked saving

in labor, cost and time, together with improved quality of product may be attained in canning operations by adoption of the process set forth. Unvarnished labels may 60 be purchased at low cost and the varnish or lacquer as applied in the present process in addition to producing a higher gloss on the label, effects a simultaneous sealing of minute holes and excludes atmosphere from 65 contacting with the metallic surfaces of the can, in this manner effectively preventing corrosion and rust.

Having described a preferred embodiment 70 of the invention which is desired to be secured by Letters Patent and claimed as new is:

1. The process of treating cans which comprises the steps of labeling the cans while hot, spraying the cans to deposit thereon a 75 protecting glossy coating of material, and cooling the sprayed cans.

2. The process as set forth in claim 1, in which the cooling of the cans is only partial, together with the step of packing the partially cooled cans for shipment. 80

3. A process of treating sealed cans containing materials packed in a partial vacuum which comprises the steps of labeling the cans, and passing the labeled cans through 85 an extended spray of coating material to deposit thereon a thin uniform coating of protecting material which hardens sufficiently as applied to prevent the coating from being forced into minute holes existing 90 in the cans and of sufficient thickness to effectively seal any minute holes and preserve the existing vacuum in the cans.

4. The process as set forth in claim 3 in which the cans are labeled and passed 95 through said spray while hot.

5. A process of treating sealed cans containing foods packed in a partial vacuum which comprises the steps of applying colored labels to the cans while hot, passing the 100 labeled cans while still hot to deposit thereon a uniform coating of glossing and protecting material which hardens sufficiently as applied to prevent the coating from being forced into minute holes existing in the cans, 105 and drying the coating on said cans.

6. The process as set forth in claim 5 in which the drying of the coating is only partial together with the step of packing the partially dried cans for shipment.

In testimony whereof, I affix my signature.
WALTER H. BENTLEY.
